UNITED STATES PATENT OFFICE.

HARRY ROTHENBERG, OF RIDGEWOOD, NEW YORK.

DESIGN FOR A SWITCH-SLIDE FOR PORTABLE ELECTRIC LIGHTS.

51,241.

Specification for Design.

Patented Sept. 4, 1917.

Application filed June 3, 1916. Serial No. 101,617. Term of patent 7 years.

To all whom it may concern:

Be it known that I, HARRY ROTHENBERG, a citizen of the United States, residing at Ridgewood, in the county of Queens and State of New York, have invented a new, original, and ornamental Design for a Switch-Slide for Portable Electric Lights, of which the following is a specification, reference being had to the accompanying drawings, forming a part thereof, and in which—

Figure 1 is a front view, and
Fig. 2 a side view of a switch-slide for

portable electric lights embodying my design.

I claim:

The ornamental design for a switch-slide for portable electric lights, as shown.

HARRY ROTHENBERG.
